IRON SUPPORT

Joseph Lefkowitz, Brooklyn, N. Y.

Application February 17, 1937, Serial No. 126,269

4 Claims. (Cl. 38—96)

The present invention relates to supports for electric irons and has for its principal object to provide a device of this character detachably secured to one of the handle straps of the iron and adapted to support the iron upon its side in an elevated position.

A further object of the invention is to provide an adjustable clamping member for clamping the support to the handle strap of the iron and capable of accommodating handle straps of various widths and thicknesses.

A still further object is to provide a device of this character of simple and practical construction, strong and durable, efficient and reliable in performance, relatively inexpensive to manufacture, easy to install in operative position upon the iron and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout and in which:—

Figure 1 is a side elevational view of an electric iron showing the support in position thereon.

Figure 2 is a front elevational view showing the iron in supported position.

Figure 3 is a sectional view through one of the handle straps taken substantially on a line 3—3 of Figure 1.

Figure 4 is a top plan view of the support removed from the iron.

Figure 5 is an end elevational view of the sleeve forming part of the clamping member.

Figure 6 is a side elevational view of a modified form of support.

Figure 7 is a top plan view thereof.

Figure 8 is an end elevational view.

Referring now to the drawings in detail, wherein for the purpose of illustration I have disclosed a preferred embodiment of the invention, the numeral 5 designates an electric iron of conventional construction which includes a handle 6 connected to the iron by a strap member 7.

The support comprises an arm 8 of strap material having a slotted opening 9 through which extends a carriage bolt 10 having a head 11 engaging one edge of the forward strap 7 of the iron, the opposite edge of the strap resting upon a shoulder 12 formed on one side of a sleeve 13 mounted upon the bolt.

As more clearly illustrated in Figure 3 of the drawings the shoulder 12 is cut at an acute angle relative to the longitudinal axis of the sleeve and

a portion of the side wall of the sleeve is cut out as shown at 14 to enable the strap 7 to lie flatly against the shank of the bolt 10. The end of the sleeve opposite from the cut out portion is provided with teeth 15 in biting engagement with the arm 8 to prevent slipping of the arm after having been secured in adjusted position. The end of the bolt is provided with a wing nut 17 for securing the parts in clamped position as illustrated in Figures 2 and 3 of the drawings.

The rear end of the arm 8 is formed with a right angularly extending portion 18 projecting outwardly toward the side of the iron and terminating in a pair of spaced parallel legs 19 and 20 formed on the upper and lower edges of the 15 section 18 and extending longitudinally in outwardly spaced relation from the side of the iron as will be clearly apparent from an inspection of Figure 2 of the drawings. The leg 20 also extends downwardly toward the base of the iron to properly cooperate with the leg 19 in supporting the iron in a balanced elevated position.

The support formed of the arm 8, right angle section 18 and the spaced parallel legs 19 and 20 may be constructed integrally as shown in Figures 1, 2 and 4, or these parts may be formed of separate elements as shown in the modified form of the invention illustrated in Figures 6, 7 and 8.

In this modified form, the arm is designated by the numeral 21 and includes the parallel end portions 22 and 23 connected by the right angle section 24. The end 22 is provided with the slot 25 and the end 23 is formed with oppositely bent up lugs 26 and 27 clamping the intermediate side portions 28 of the open frame 29 therebetween. 35 The ends of the frame are bent outwardly from the iron to form the parallel legs 30 and 31.

It is believed the details of construction and operation of the device will be clearly apparent from the foregoing without further detail explanation thereof.

Having thus described the invention what I claim is:—

1. An iron support comprising a pair of spaced parallel legs projecting laterally from one side of the iron, and having supporting edges extending longitudinally of the iron, said iron having a pair of handle straps, an arm having a slotted opening, said arm being offset longitudinally from the leg in the direction of the iron and a clamping member adjustably positioned in the opening and detachably securing the arm to one of the handle straps of the iron to adjust the arm and legs longitudinally with respect to the iron.

2. An iron support comprising a pair of spaced 55

parallel legs projecting laterally from one side of the iron, and having supporting edges extending longitudinally of the iron, said iron having a pair of handle straps, an arm extending forwardly of the legs having a slotted opening, said arm being offset longitudinally from the leg in the direction of the iron, a bolt adjustably positioned in the opening and having a head in clamping engagement with one edge of one of the handle straps of the iron to adjust the legs longitudinally with respect to the iron, a sleeve mounted on the bolt having a shoulder in clamping engagement with the opposite edge of said strap and means for securing the arm on the bolt and securing the sleeve and bolt in clamping position.

3. A support for an iron having a pair of handle straps comprising a pair of spaced parallel legs projecting laterally from one side of the iron and extending longitudinally thereof, an arm extending forwardly of the legs having a slotted

opening, a bolt adjustably positioned in the opening and having a head in clamping engagement with one edge of one of the handle straps of the iron, to adjust the legs longitudinally with respect to the iron, a sleeve mounted on the bolt having a shoulder in clamping engagement with the opposite edge of said strap, friction clutch means between the sleeve and arm, and a nut carried by the bolt securing the arm and sleeve thereon.

4. A support for an iron having a pair of handle straps comprising an arm having its ends offset, means for clamping one of said ends of the arm to the handle strap of the iron, an open frame member having parallel ends bent to form a pair of supporting legs, and lugs on the other of said ends of the arm engaging an intermediate portion of said frame to secure the same to said arm.

JOSEPH LEFKOWITZ. 20
